UNITED STATES PATENT OFFICE.

WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE.

TOILET-PAPER PACKAGE.

1,038,457.

Specification of Letters Patent. Patented Sept. 10, 1912.

Application filed February 7, 1910. Serial No. 542,575.

To all whom it may concern:

Be it known that I, WILLARD E. SWIFT, a citizen of the United States, residing at Worcester, in the county of Worcester and 5 Commonwealth of Massachusetts, have invented a new and useful Improvement in Toilet-Paper Packages, of which the following is a specification, accompanied by drawings forming a part of the same, in which—
10 Figure 1 represents a perspective view of one of my improved toilet paper packages. Fig. 2 is an end view. Fig. 3 is a perspective view showing the cardboard reinforcement of the package turned at right angles
15 to the under side of the package in position for insertion in a cabinet. Fig. 4 is a diagrammatic view illustrating the method of folding the sheets of paper to form the package. Fig. 5 is a sectional view of a cabinet
20 net designed to hold my improved package.

Similar reference characters refer to similar parts in the different views.

My present invention relates to that class of toilet paper packages in which the sheets 25 of paper are folded lengthwise at their center with the folded half of each sheet inclosed in the folds of the contiguous sheets so that when one sheet is drawn from the cabinet by its edge, the edge of the next succeeding 30 sheet will also be withdrawn from the cabinet in position to be seized by the hand.

The objects of my invention are to provide an improved method of applying bands to inclose the package; to enable the bands 35 to be retained in place until the package has been inserted in a toilet cabinet; and also to provide means to facilitate the insertion of the edge of the lowermost sheet through a slit in the cabinet, and these objects I accomplish in the manner hereinafter described and pointed out in the annexed claims.

Referring to the accompanying drawings 1 denotes a package of folded toilet paper 45 shown in perspective view in Fig. 1, which represents one of my improved packages, and the top side of the figure represents the lowermost side of the package when the same is inserted in the cabinet. The several 50 sheets are folded at their centers lengthwise, with the folded half of each sheet inclosed within the folds of the next contiguous sheet, as represented in diagrammatic view in Fig. 4, in which the upper half 2 of 55 the lowermost sheet is folded over the lower

half 3 of the second sheet, and the upper half 4 of the second sheet is folded over the lower half 5 of the third sheet, and so on throughout the package. The outer edge of the lowermost sheet is folded over to form a 60 narrow flap 6 which is pasted to one edge of a cardboard reinforcement 7, which is stiff enough to be conveniently inserted through a slit 8 in the bottom of the cabinet 9. The paper bands 10 are then wrapped around the 65 package, with the ends 11 and 12 pasted to opposite sides of the cardboard reinforcement. The cardboard reinforcement is then folded flat against one side of the package for convenience in handling the package. 70 The bands 10 are weakened by a row of transverse perforations 13 in alignment with the edge 14 of the cardboard reinforcement.

In inserting the package in the toilet cabinet 9 the hinged cover 15 is raised and the 75 package inserted, with the side provided with the cardboard reinforcement downward, and with the cardboard reinforcement suspended beneath the package at right angles thereto, as shown in Figs. 2 and 3. 80 The lower edge 16 of the cardboard reinforcement is entered in the slit 8 of the cabinet and pushed through the bottom of the cabinet by pressing the package downward. When the package rests upon the bottom of 85 the cabinet a weight 17 is placed on the top of the package to hold the package in constant contact with the bottom of the cabinet as the lowermost sheets are successively withdrawn. A forcible pull upon the projecting cardboard 7 will sever the inclosing bands 10 on the lines of the perforations 13, allowing the lowermost sheet to be drawn through the slit 8 by its attachment to the cardboard 7. As the upper half 2 of the 90 folded lowermost sheet is withdrawn through the slit 8, the edge of the lower half 3 of the second sheet will also be withdrawn through the slit and left suspended below the bottom of the cabinet far enough to be seized by the 95 operator.

I am aware that the method of reentering the individual sheets of paper to form a package so that the withdrawal of one sheet will expose the edge of the next succeeding sheet, is not new. I am also aware that such folded packages have heretofore been fastened by means of inclosing bands or wrappers for convenience in transmission. Such folded packages, however, have re- 100 105 110

quired the loosening of the bands or inclosing wrapper before the package was inserted in the cabinet, which prematurely loosened the folded sheets and made the manipulation of the folded package difficult.

By means of my present invention the bands are not loosened for the release of the folded paper sheets until after the package has been placed in position, and the edge of the first or lowermost sheet projected through the slit in the cabinet. The bands are then severed by the act of withdrawing the first sheet. The insertion of the edge of the sheet in the slit of the cabinet is also made much easier by the employment of the cardboard reinforcement.

I claim,

1. A toilet package, comprising interfolded sheets of paper, a strip of stiff material attached at its edge to the edge of

one of said interfolded sheets and at the center of one side of the package, and a band inclosing the package having its ends attached to opposite sides of said strip of stiff material.

2. A toilet package, comprising interfolded sheets of paper, a strip of stiff material attached at its edge to the edge of one of said interfolded sheets and at the center of one of the sides of the package, a band inclosing the package having its ends united to the attached edge of said stiff strip, said band having transverse weakened lines adjacent to its attached ends and on opposite sides of said strip of stiff material.

Dated this third day of February 1910.

WILLARD E. SWIFT.
